PULVERIZER MILL

Harry R. Collins, Allentown, Pa.; May H. Collins
administratrix of said Harry R. Collins, deceased

Application October 21, 1936, Serial No. 106,906

19 Claims.

(Cl. 83—45)

This invention relates to pulverizer mills especially intended for the reduction of non-metallic materials such as coal, limestones and cement clinker, and in its more specific aspects pertains to improvements in grinding assemblies therefor of the type preferably comprising a plurality of annular series of grinding elements, such as balls, which cooperate with grinding surfaces, at least one of which is rotatably driven in a horizontal plane to actuate the balls.

Among the objects of the present invention may be noted the provision of an improved grinding assembly for pulverizing mills, by which reduction of the material under treatment is accomplished in a plurality of stages, the invention contemplating an arrangement in which the grinding assembly of the stated character is symmetrically disposed about a vertical axis which constitutes the axis of the drive shaft for the rotating grinding surface or surfaces of the assembly, thereby to reduce twisting and/or torsional strains to safe limits. Preferably also, the grinding assembly is arranged as an independent unit below the driving mechanism for the drive shaft, with the grinding assembly being capable of assembly exteriorly of the mill casing for lowering thereinto as a unit. There is also provided a construction in which, upon removal of the driving mechanism, the grinding assembly may be readily lifted from the mill casing for replacement of worn parts as is or may be necessary.

A further object of the present invention is the provision of a grinding assembly in which the weight of certain parts thereof is carried by a series of the grinding elements, thus to apply grinding pressure thereto, and in which the grinding pressures may be adjusted to the material under treatment in a simple manner and by readily accessible means, with provision being made for the regulation of the degree of fineness of the product to satisfy varying requirements.

A further object of the invention is the provision of an improved grinding assembly of the stated character, which is self-centering, and in which provision is made for compensation of wear occurring on the grinding balls and/or the grinding surfaces with which the latter cooperate, and which is further so designed that tramp material may pass through the mill without injury to the grinding surfaces or elements. To this end the rotatable grinding surface or surfaces are each resiliently supported from a rotating part of the grinding assembly in independent manner, so that strains encountered by

one may be suitably taken up without transmission to the other. Among the advantages of this latter arrangement may be noted enhanced flexibility, reduced cost, and lesser wear, all by reason of the fact that ordinary grinding stresses, as well as stresses occurring by reason of the existence of tramp particles in the material being pulverized, are substantially reduced by reason of the fact that each rotary grinding surface is capable or substantially so of taking up through its unique mounting stresses encountered by it.

Other objects will be in part obvious and in part hereinafter pointed out in connection with the accompanying drawings illustrating in detail certain embodiments of the invention.

In these drawings, wherein like reference characters designate like parts throughout the several views,—

Fig. 1 is an elevation, partly in section along lines 1—1, Fig. 2, of a pulverizing mill embodying the improved grinding assembly, certain parts being omitted for the sake of clearness;

Fig. 2 is a partial plan view of the grinding assembly;

Fig. 3 is a section generally along lines 3—3 of Fig. 2;

Fig. 4 is a broken-away detail in section of a modified construction.

Referring to the drawings and more particularly to Figs. 1, 2 and 3, reference character 10 designates generally a cylindrical casing constituted by a lower casing section 11 provided with a bottom annular flange 12 which may serve as a bed plate for the apparatus, and an upper section 13. Between the casing sections 11 and 13 is arranged a main bearing support 14 with bolts or equivalent securing means 15 removably securing the bearing support 14 to facing flanges of the aforesaid casing sections. The upper casing section 13 is provided with a horizontal top plate serving to close the top of the casing 10 as formed by the casing sections aforesaid, and arranged on the top plate and suitably secured thereto is a vertically disposed motor 16, the motor shaft (not shown) of which extends into the chamber or compartment formed by the casing section 13 and the main bearing plate 14. Arranged in said compartment is a speed reduction mechanism, of which the circular supporting plate 20 of a ring gear (not shown) is indicated, the reduction gearing being driven by the motor shaft aforesaid. The supporting plate 20 of the ring gear is secured as by bolts 22 to a flange formed on the upper end of a main driving shaft 55

23, the upper portion of which is circular in cross section. Motor 16 through speed reduction gearing thus provides a drive for the main driving shaft 23.

5 The main bearing plate 14 is provided with a central, elongated hub 25 disposed about the circular portion of the shaft 23, there being provided suitable bearings between said hub and shaft, provision being made for lubricating said 10 bearings, as well as the speed reduction gear as aforesaid. These elements are not shown and described in detail as they form no part of the present invention except in so far as they may enter into certain broad combinations herein- 15 after set forth.

The lower end of the main drive shaft 23 extends downwardly into the mill casing section 11 and is of square or other angular section. The squared lower end of said driving shaft extends 20 through central openings in upper and lower rotary grinding rings designated 30 and 31, respectively, and through upper and lower cage rings 32 and 33, respectively, the openings in 25 said grinding and cage rings being of the same cross section as the lower end of the driving shaft, but being slightly larger whereby the shaft may be withdrawn from the rings and to permit the rings free vertical movement as 30 well as some horizontal movement, thus to maintain alignment and to accommodate for possible 35 inaccuracies in manufacture or normal wear of the grinding elements. It will be understood that the squared end of the driving shaft 23 provides a driving connection between said shaft and the grinding and cage rings as aforesaid.

Between the upper and lower grinding rings 30 and 31 is an intermediate fixed ring 35 supported on an inwardly extending shelf or ledge 36 formed on the inner wall of the casing section 11. On the upper face of the fixed ring 35 is arranged a circumferentially channeled raceway 38, suitably secured to the fixed ring, for an upper annular series of grinding balls 40, on 40 the upper portions of which engage a circumferentially channeled raceway 41 secured to the under face of the rim portion of the upper rotating ring 30. By this arrangement the weight of the upper ring 30 and of the grinding balls 40 is carried by the fixed ring 35, with the grinding balls 40 and the grinding surfaces provided by the raceways 38 and 41 thus forming an upper grinding stage.

On the under face of the fixed ring 35 is suitably secured a circumferentially channeled raceway 43 against which engages a lower annular series of grinding balls 44 carried by a circumferentially channeled raceway 45 secured to the upper surface of the rim portion of the lower rotating ring 31. The said grinding balls 44, in conjunction with the raceways 43 and 45, constitute the lower grinding stage of the grinding assembly.

Referring now to Fig. 3, upper and lower cage rings 32 and 33 are secured to each other by a plurality of through bolts 50, the lower ends of which are preferably headed, the upper ends each being suitably threaded to receive a spacing nut 51 and a locking nut 52, between which latter the upper cage ring 32 is disposed. Said through bolts pass through suitable apertures 53, 54, provided in the rotating grinding rings 30, 31, respectively, the bolts passing freely through said apertures and being devoid of connection with 70 said grinding rings. By the aforesaid arrange- 75

ment, cage rings 32, 33 and through bolts 50 form a cage which is driven by the shaft 23 to rotate with the grinding rings 30, 31, the spacing between the cage rings being relatively fixed by suitable manipulation of the spacing and lock nuts 51, 52, and the cage being positioned vertically by engagement of cage ring 32 with a shoulder 55 formed on driving shaft 23 intermediate its upper circular and lower squared portions, as will be described hereinafter.

Grinding pressure in excess of that afforded by the weight of the upper grinding ring 30 acting on the grinding balls 40 may be supplemented by a series of compression springs 60 (one being shown in Fig. 1), which react between the under face of the cage ring 32 and the top surface of the grinding ring 30. The said springs 60 are seated in upwardly opening, spaced spring pockets 61 in the upper grinding ring 30, their upper ends bearing against spring heads 62 with which cooperate compression bolts 64 extending through the top cage ring 32. By adjusting the bolts 64 to vary the compression of springs 60, grinding pressures may be varied. Lock nuts 63 are provided whereby compression of springs 60 may be set at a predetermined pressure.

The lower cage ring 33 is disposed below the hub and intermediate portion of the lower grinding ring 31 and is preferably provided with a horizontal rim portion, between the upper face of which and the under surface of the lower grinding ring 30 is arranged a plurality of compression springs 65 seating in ring pockets 66 and providing a resilient support for the lower grinding ring. The compression of the springs 65 may be adjusted by means of compression bolts 67 and associated lock nuts 68.

By the above described arrangement, compression springs 60 exert a resilient, downward pressure on the grinding balls 40 of the upper grinding stage, and compression springs 65 exert an upward grinding pressure on the grinding balls 44 of the lower grinding stage. Preferably, springs 60 and 65 are arranged coaxially and spaced uniformly about the axis of the drive shaft 23 on the same circle on which through bolts 50 are arranged, the sets of upper and lower springs alternating with the through bolts, as generally indicated in Fig. 2. While in the construction illustrated four sets of compression springs spaced at an angle of 90° and alternating with through bolts in the manner specified are contemplated, the number of the springs and/or bolts and their relative arrangement may vary in accordance with design requirements.

It will further be noted that the circumferential channels of the raceways 38, 41, and 43, 45, have substantially the same curvature as the grinding balls 40, 44, and that the several grinding surfaces and the balls are vertically aligned. Accordingly grinding pressures are at all times exerted in a vertical direction.

In order to direct appropriately the flow of material through the mill, the upper grinding ring 30 is provided with a vertically disposed flange 70, to which is bolted or otherwise secured a circular upwardly extending dam 71. Secured to the peripheral edge of the ring 30 is an outwardly and downwardly inclined baffle 72 which terminates short of a reversely inclined baffle 73 secured, for example, to the peripheral edge of the lower raceway 38 of the upper grinding stage. Between the baffles 72 and 73 is a gap of suitable dimension as to pass material to the relatively outer side of the grinding balls 40 of the 75

upper stage. The inner peripheral edge of the lower raceway 38 of the upper grinding stage may carry an inclined dam 74 over which material reduced in the upper grinding stage passes and drops downwardly between the inner peripheral edge of the fixed ring 35 and the intermediate, inclined upper surface of the lower rotating ring 31. Carried on the peripheral edge of the lower ring 31 and outwardly of the grinding balls of the lower stage is an adjustable height dam 75 carrying along its top edge a screen 76. By the aforesaid arrangement, material spouted into the mill casing through the inlet opening 77 thereof is directed on to the upper rim surface of the rotating grinding ring 30. Centrifugal force, due to rotation of said ring, thereupon causes such material to be thrown outwardly whereupon it drops on the baffle 72 and is thence directed to the outer side of the grinding balls 40 of the upper stage by the lower baffle 73, the flow of material being inwardly through the annular series of grinding balls 40. The inner dam 74 prevents discharge of material from the upper stage until it has been suitably reduced whereupon material flows over the edge of the dam 74 and is directed to the inner side of the grinding balls of the lower grinding stage, the flow of material being outwardly through the annular series of grinding balls 44. The adjustable height dam 75 controls discharge of the pulverized material until it has been reduced to the desired degree of fineness whereupon the product of final size passes through the screen 76 and, falling downwardly, is picked up by air entering a forwarding fan (not shown) through air inlet openings 78 formed in the lower casing section 11.

A grinding assembly as described in the foregoing constitutes a unitary assembly which may be assembled outside of the mill casing on an assembling shaft which is a counterpart of the squared lower end of driven shaft 23 and thereupon lowered into the casing as a unit. The assembly is supported within the casing by the ledge or shelf 36 coacting with the fixed grinding ring 35, bolts 80 being provided to maintain the fixed ring 35 seated on the shelf ring 36.

Upon withdrawal of the driving mechanism, including the main driving shaft 23, the grinding assembly as aforesaid may be removed as a unit from the casing, in which event holding bolts 80 may be unthreaded and raising bolts 81 may be manipulated to disturb the seating relation of the fixed ring 35 whereupon the grinding assembly may be lifted from the casing.

The provision as aforesaid of upper compression springs 60 acting on the upper rotating grinding ring and of lower compression springs 65 acting on the lower rotating grinding ring permits independent adjustment of the grinding pressures in the upper and lower stages and at the same time permits each of the rotating grinding rings to take up stresses which it individually encounters without transmitting such stresses relatively to the other ring. Accordingly, relatively light compression springs may be utilized and there results an economy in manufacture and a greater flexibility in use.

In the construction so far described, the cage structure formed by the rings 32, 33 and through bolts 50 is rotatably driven with the grinding rings 30, 31, from the drive shaft 23, and while the cage is capable of vertical movement, it is limited in its upward movement by engagement of the upper ring 32 against the drive shaft

shoulder 55. The parts are so proportioned and arranged and the strength and compression of springs 60 with respect to springs 65 are so selected that in normal operation cage ring 32 always bears against shoulder 55, with the result that springs 60 and 65 have in effect fixed points of reaction.

In Fig. 4, wherein is illustrated a modified construction, the lower grinding ring 31A is resiliently supported from a spring abutment ring 10 33A which in turn is carried by a collar 33B threaded on to the circular threaded end of the driving shaft 23A, and locked thereto as by cap screws 33C which are preferably wired for safety. Compression springs 65A react against the abutment ring 33A and exert adjustable grinding pressure on the lower grinding balls in the manner described. An upper abutment ring generally similar to the top cage ring 32, and the upper rotary grinding ring as described in relation to Figs. 1-3, are provided. However, in the modification described, the through bolts 50 previously described are eliminated, temporary assembly bolts (not shown) which extend between top and bottom spring abutment rings being utilized in their place during assembly and placement of the grinding assembly in the casing. Upon connection of the collar 33B to shaft 23A as stated, such temporary holding bolts may be removed, and the related sets of upper and lower 30 compression springs thereupon function in the manner described in the Figs. 1-3 construction. To remove the grinding assembly as aforesaid, the temporary holding bolts are replaced and lower collar 33B is disconnected from the driving shaft, access being had through the lower end of the casing 10. Upon removal of the driving mechanism including the driving shaft as aforesaid, the modified grinding assembly may be bodily lifted from the casing for repair or 40 replacement of its parts.

As many changes could be made in carrying out the above constructions without departing from the scope of the invention, it is intended that all matter contained in the above description, or shown in the accompanying drawings, shall be interpreted as illustrative and not in a limiting sense.

I claim:

1. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, a driving shaft extending through said openings and operative to drive the rotating rings, spring means for exerting yielding downward pressure on the grinding elements of the upper series, spring means for exerting yielding upward pressure on the grinding elements of the lower series, each said spring means including a plurality of springs and a member against which said springs react, and a drive connection between the driving shaft and said members, whereby both said spring means rotate with the rotating grinding rings.

2. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided

- with a central shaft opening, a driving shaft extending through said openings and operative to drive the rotating rings, spring means for exerting yielding downward pressure on the grinding elements of the upper series, spring means for exerting yielding upward pressure on the grinding elements of the lower series, each said spring means including a plurality of springs, a member against which said springs react, and means carried by said member for adjusting said springs to the desired pressure, and a drive connection between the drive shaft and said members, whereby both said spring means are rotatable with the rotating grinding rings.
3. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, a spring reacting ring arranged above said upper grinding ring, a spring reacting ring arranged below the lower grinding ring, independently operable sets of springs disposed between said spring rings and the upper and lower grinding rings respectively, a driving shaft extending through the central openings of the rotating grinding rings, and means providing a driving connection between the drive shaft and the spring rings.
4. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, a spring reacting ring arranged above said upper grinding ring, a spring reacting ring arranged below the lower grinding ring, said spring rings each having a central shaft opening, a driving shaft extending through said openings and operative to drive the rotating grinding rings and the spring rings, and independently operable sets of springs arranged between the spring rings and the upper and lower grinding rings respectively.
5. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, a rotating cage structure supported from the grinding elements of the upper series in operative relation to said rotating grinding rings, means carried by said cage structure for supporting the lower grinding ring and for exerting independent yielding pressure on the upper and lower grinding rings, and a driving shaft extending through the central openings of the grinding rings and having a driving connection with said cage structure.
6. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, an upper cage ring operatively related to said upper rotating grinding ring, a lower cage ring supported from the

upper cage ring in operative relation to the lower rotating grinding ring, the cage rings having central shaft openings, a driving shaft extending through the grinding and cage ring openings, and means operative between the upper and lower cage rings and the upper and lower rotating grinding rings, respectively, for exerting resilient pressure on said rotating grinding rings.

7. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, spaced cage rings, the upper of which is operatively related to the upper rotating grinding ring and the lower is supported from the upper cage ring in operative relation to the lower rotating grinding ring, the cage rings having central shaft openings, a driving shaft extending through the grinding and cage ring openings, and means operative between the upper and lower cage rings and the upper and lower rotating grinding rings, respectively, for exerting yielding pressure on the rotating grinding rings.

8. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, upper and lower cage rings operatively related to the upper and lower rotating grinding rings, respectively, and being each provided with a central shaft opening, means securing said cage rings in spaced relation, a plurality of springs operative between the upper cage ring and the upper grinding ring, a plurality of springs operative between the lower cage ring and the lower grinding ring, and a driving shaft extending through the shaft openings of the rotating grinding and cage rings.

9. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, upper and lower cage rings operatively related to the upper and lower rotating grinding rings, respectively, and being each provided with a central shaft opening, through bolts extending between said cage rings and operative to space the same, a plurality of springs operative between the upper cage ring and the upper rotating grinding ring, a plurality of springs operative between the lower cage ring and the lower rotating grinding ring, and a driving shaft extending through the shaft openings of the rotating grinding and cage rings, whereby the cage rings and the springs are rotated with the rotating grinding rings.

10. In a pulverizer mill, the combination of upper and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, an upper cage ring operatively related to the upper grinding ring,

5 a lower cage ring operatively related to the lower grinding ring, the cage rings being each provided with a central shaft opening, through bolts extending between said cage rings and through the upper and lower grinding rings for spacing the cage rings, upper compression springs operative between the upper cage and grinding rings, lower compression springs operative between the lower grinding and cage rings, and a driving shaft 10 extending through the shaft openings of the rotating grinding and cage rings, whereby the cage rings and the springs are rotated with the rotating grinding rings.

11. In a pulverizer mill, the combination of upper and lower rotating grinding rings, an intermediate fixed grinding ring, upper and lower annular series of grinding elements disposed between the upper and intermediate rings and between the intermediate and lower rings, the upper 15 and lower grinding rings being each provided with a central shaft opening, an upper cage ring operatively related to the upper grinding ring, a lower cage ring operatively related to the lower grinding ring, the cage rings being each provided 20 with a central shaft opening, through bolts extending between said cage rings and through the upper and lower grinding rings for spacing the cage rings, upper compression springs operative between the upper cage and grinding rings, lower compression springs operative between the lower grinding and cage rings, a driving shaft 25 extending through the shaft openings of the rotating grinding and cage rings, whereby the cage rings and the springs are rotated with the rotating grinding rings, and means for adjusting the compression of the upper and lower springs independently of each other.

12. In a pulverizer mill, the combination of upper and lower rotating grinding rings, an intermediate fixed grinding ring, upper and lower annular series of grinding elements between the upper and intermediate rings and between the intermediate and lower rings, a driving shaft, a driving connection between the shaft and the 40 rotating grinding rings, the upper rotating ring resting on the upper annular series of grinding elements, a supporting ring member effectively disposed below the lower rotating grinding ring, a driving connection between the driving shaft and the supporting ring member, and means supporting the lower grinding ring from the supporting ring member.

13. In a pulverizer mill, the combination of upper and lower rotating grinding rings, an intermediate fixed grinding ring, upper and lower annular series of grinding elements between the upper and intermediate rings and between the intermediate and lower rings, a driving shaft, a driving connection between the shaft and the 45 rotating grinding rings, the upper rotating ring resting on the upper annular series of grinding elements, a supporting ring member effectively disposed below the lower rotating grinding ring, a driving connection between the driving shaft and the supporting ring member, said means including springs for exerting yielding pressure on the lower grinding ring.

14. In a pulverizer mill, the combination of upper and lower rotating grinding rings, an intermediate fixed grinding ring, upper and lower annular series of grinding elements between the upper and intermediate rings and between the 50 intermediate and lower rings, a driving shaft, a

driving connection between the shaft and the rotating grinding rings, the upper rotating ring resting on the upper annular series of grinding elements, a supporting ring member effectively disposed below the lower rotating grinding ring, a driving connection between the driving shaft and the supporting ring member, and a plurality of springs seating on the supporting ring member and operative therebetween and the lower grinding ring. 10

15. In a pulverizer mill, the combination of upper and lower rotating grinding rings, an intermediate fixed grinding ring, upper and lower annular series of grinding elements between the upper and intermediate rings and between the intermediate and lower rings, a driving shaft, a driving connection between the shaft and the rotating grinding rings, the upper rotating ring resting on the upper annular series of grinding elements, means rotating with the upper grinding 20 ring for exerting yielding pressure thereon, a collar carried by the driving shaft and rotating therewith, and means yieldingly supporting the lower driving ring from said collar.

16. In a pulverizer mill, the combination of upper and lower rotating grinding rings, an intermediate fixed grinding ring, upper and lower annular series of grinding elements between the upper and intermediate rings and between the intermediate and lower rings, a driving shaft, a driving connection between the shaft and the rotating grinding rings, the upper rotating ring resting on the upper annular series of grinding elements, means rotating with the upper grinding 25 ring for exerting yielding pressure thereon, a supporting collar carried by the driving shaft and disposed generally below the lower grinding ring, and a plurality of springs carried by the collar and operative between the collar and the lower grinding ring to exert yielding pressure on the 30 lower grinding ring.

17. In a pulverizer mill, the combination of a casing, a fixed grinding ring carried thereby, an upper annular series of grinding elements carried by the fixed grinding ring, an upper rotating 45 grinding ring carried by said elements, a rotating ring element arranged above the rotating grinding ring driving means, means including said driving means for limiting upward movement, of said ring element, means including said ring element for exerting yielding pressure on the upper ring, a lower rotating grinding ring, a lower annular series of grinding elements carried thereby and engaging the fixed grinding ring, and means carried by said driving means for supporting the 50 lower grinding ring.

18. In a pulverizer mill, the combination of a casing, a fixed grinding ring carried thereby, an upper annular series of grinding elements carried by the fixed grinding ring, an upper rotating 60 grinding ring carried by said elements, a rotating ring element arranged above the rotating grinding ring, springs arranged between said ring element and the upper grinding ring operative to exert yielding pressure on the upper ring, a lower 65 grinding ring, an annular series of rotating grinding elements carried thereby and engaging the fixed grinding ring, the upper and lower grinding rings and the ring element being provided with a shaft opening, a driving shaft extending through said opening, means on the shaft limiting upward movement of the ring element, and means carried by said driving shaft for supporting the lower grinding ring. 70

19. In a pulverizer mill, the combination of up- 75

per and lower rotating grinding rings, an intermediate fixed grinding ring, upper and lower annular series of grinding elements disposed between the upper and intermediate rings and between the intermediate and lower rings, the upper and lower grinding rings being each provided with a central shaft opening, a rotating cage structure supported from the grinding elements of the upper series in operative relation to said 10 rotating grinding rings, means carried by said

cage structure for supporting the lower grinding ring and for exerting independent yielding pressure on the upper and lower grinding rings, a driving shaft extending through the central openings of the rotating grinding rings and having a driving connection with said cage structure, and means for positioning vertically the cage structure with reference to the driving shaft. 5

HARRY R. COLLINS. 10
